United States Patent Office.

JOSEPH A. RUFF, OF SOMERVILLE, MASSACHUSETTS, ASSIGNOR TO THE RUSSELL & ERWIN MANUFACTURING COMPANY, OF NEW BRITAIN, CONNECTICUT.

Design No. 3,825, dated January 25, 1870.

DESIGN FOR DOOR-ESCUTCHEON.

The Schedule referred to in these Letters Patent and making part of the same.

I, JOSEPH A. RUFF, of Somerville, in the county of Middlesex, and State of Massachusetts, have invented and produced a new and original Design for a Door-Escutcheon, of which the following is a specification.

The outlines of the design, shown in the accompanying photographic view, are mainly composed of curved lines, but of straight lines sufficient to form the square wings *a a*, at the base.

It is mainly bordered by a plain raised moulding, *b*, the knob-escutcheon, *A*, being bordered by a circular band, *c*.

On the right and left of the knob-escutcheon *A*, is an ornamental device, *e e*, consisting of a floral leaf.

The space enclosed by the moulding *b* is a fine matted ground, filled with raised ornamental floral leaves and scroll-work.

I claim, as my invention—

The ornamental design for door-escutcheons, substantially as described and shown in the photograph.

Witnesses: JOSEPH A. RUFF.
